HEAT REGULATING DEVICE

Earle W. Ballantine, Chicago, Ill., assignor to
 Solar Industries, Inc., Chicago, Ill., a corpora-
 tion of Illinois

Application March 15, 1934, Serial No. 715,787

3 Claims. (Cl. 158—28)

This invention relates to improvements in heat regulating devices and more particularly to improvements in interlocked electric circuits controlling burner motors and ignition apparatus associated therewith, of the general class disclosed in Patent No. 1,727,308.

The objects of my invention are to provide means whereby a burner fuel feeding motor can be started when there is a call for heat; to provide means to stop the burner motor when sufficient heat has been obtained; to provide fuel and means for ignition; to provide means whereby after flame is obtained, the ignition means is disconnected; to provide for the interruption of the fuel supply at the end of a predetermined time, ninety seconds in this particular embodiment of my device, in case flame or ignition is not successfully obtained; to prevent restarting of the burner motor or ignition means after power failure, until the system is in proper condition; and generally to provide means insuring safety throughout the system and economy of burner and ignition operation.

Other objects of my invention are to provide for an ignition timing cycle, by means of a timing switch or equivalent device, which functions whenever the motor is energized and is so arranged as to open the motor and ignition circuits within a predetermined time, unless said timing device is shorted out of the circuit previous to the expiration of this time; to provide a thermostatic device which allows closing of the motor and ignition circuits only when a predetermined temperature has been reached; to provide means whereby the timer device cannot operate when ignition has been successful unless the flame goes out after ignition has been obtained; to provide means whereby when flame is obtained, the ignition apparatus and the motor and starting circuit are electrically disconnected; to provide an arrangement of two relays respectively controlling the motor circuit and the ignition circuit, and the circuit through two thermostatic device, one a timing device, such that when the motor circuit and the circuit to the other thermostatic device are closed, a timing operation is initiated and controlled; to provide a thermostatic device located in the stack or otherwise conveniently positioned adjacent to the burner flame, whereby after flame is obtained, this thermostatic device will cause one relay to open the ignition circuit; to provide means whereby this last named stack control will also operate to short out the timing device after flame is obtained; to provide means whereby the stack control, when in the hot posi-

tion, will not permit completion of the motor or ignition circuits; and to provide means whereby all the above relays and thermostatic devices operate at a relatively low potential with respect to the line voltage at which the motor and ignition circuits operate.

Other objects and advantages of my invention will appear from the following description and the figure, which is a diagrammatic view of the control circuit.

In the accompanying drawing, the source of electrical power is indicated by the lines 6 and 7. The lines 6 and 7 have across them the primary 8 of the transformer 9. The secondary 10 of this transformer is connected by lead 11 to the thermostatic device 12, which is generally positioned in the room whose heat it is desired to control. This thermostatic device has an arm 13 and a contact point 14. The contact point 14 is connected by means of the lead 15 to the main relay coil 16 and by means of the lead 17 to the coil 18 of the ignition relay. The circuit from the coil 16 of the main relay is completed by the lead 19, the thermal safety switch or timing device 20 and the lead 21 to the opposite side 15 of the transformer secondary from that to which the thermostatic device 12 is connected.

The circuit through the ignition relay coil 18 continues through the lead 22 to the contact point 23 in the stack control 24. When the stack control arm 25 is in the cold position, it is in contact with the point 23 and the circuit is continued through the lead 26 to the contact arm 27. This contact arm 27 is adapted to make contact with one of two points, either point 28 or point 29. When the main relay has been energized, arm 27 is drawn into contact with point 29, and the ignition relay coil circuit is completed through the lead 30, 19, the thermal switch 20, and the lead 21 back to the source 40 of energizing current in the form of the transformer secondary 10. When the main relay is not operating, the contact arm 27 will lie against the point 28 and the leads 31, 15 and 17 will thus complete a shunt circuit back to the ignition relay coil and render that relay inoperative. The ignition relay coil controls the movement of the arm 32, and when in energized position, draws it against the contact point 33, whereby the ignition circuit is completed from the line 6 along the lead 34 through the point 33, the arm 32, the lead 35 to the ignition transformer, and thence through the leads 36 and 37 back to the other supply line 7.

Energization of the main relay coil 16 draws 55

the contact arm 27 into contact with the point 29, as before discussed, and the arm 28 into contact with the point 39, whereby the motor circuit is completed as follows: 6, 34, 40, 39, 38, and 5 41 to the motor 47, and then 37 and 7 back to the source of power supply. When the main relay is energized and stack control 24 is in the hot position, wherein the arm 25 makes contact with the point 42, the thermal safety switch 10 20 is shorted out as follows: 30, 29, 21, 26, 25, 42 and 43.

The thermal safety switch 20 is of the type which contains a heating coil 44 and a set of 15 thermostatic contacts 45 and 46, whereby after current has flowed through the heating coil for a predetermined length of time, the contacts will be broken, and will not return to operative position until they have been manually set. The 20 thermostatic device 12 is of any common single contact type sensitive to a change in their temperature of a very few degrees, suitable for mounting in a room or rooms being heated. The ignition relay 18 is of the type wherein energizing of the coil draws the arm 32 into contact with 25 the point 33, and wherein where the current ceases, contact breaks automatically. The main relay controls two contact arms, one of single contact type and the other making one contact in the energized position, and another in the 30 de-energized position. The stack control 25 is a thermostatic device making contact with one point in the cold position and with another when it is heated.

Normal operation

35 Assuming the entire circuit to have been inoperative for a reasonable length of time, and yet assuming that the room temperature has not dropped sufficiently to close the contacts in the thermostat 12, the entire circuit will be in the 40 condition illustrated in the accompanying drawing. When the room temperature drops below the desired point, the thermostat 12 closes its contacts and a circuit energizing the main relay 16 is completed as follows: 11, 13, 14, 15, 16, 45 19, 20, 21 and 10. This draws up both arms of the main relay, arm 38 closing the motor control circuit as previously described, and arm 27 making contact with point 29 to complete a circuit whereby the ignition relay 18 is energized as 50 follows: 10, 11, 13, 14, 15, 17, 18, 22, 23, 25, 26, 27, 29, 30, 19, 20, and 21. Energization of the ignition relay 18 closes the contacts 32 and 33 and completes the circuit to the ignition means as previously described.

55 If the ignition means ignites the fuel being supplied by the burner motor 47, the flames will, in a very few seconds, cause the stack control arm 25 to move over into the hot position, thus 60 making contact with the point 42 and shorting out the thermal safety switch 20 as previously described. The moving of the stack control arm 25 also breaks the ignition relay circuit at the point 23. This breaks the ignition circuit at the 65 point 33 and renders the ignition means inoperative. This places the circuit in condition to operate the burner motor for as long a time as may be necessary to warm the room to a point which will cause the thermostat 12 to break its contacts, de-energize the main relay, and thus 70 render the entire circuit inoperative. After the stack control thermostat has cooled sufficiently to return to its engagement with the point 23, the circuit will again be in the condition illustrated in the accompanying diagram, and will be 75 ready to respond to a drop in room temperature.

Operation when ignition is not obtained

As before, when the room thermostat closes, the main relay will be energized and a second thereafter the ignition relay will be energized, thereby closing the circuits of the burner motor and the ignition transformer. Assuming that ignition is not obtained, however, there will then be no rise in the temperature of the stack due to flames and, consequently, the stack control will remain in the cold position. With the stack control in the cold position, the thermal safety switch 20 carries the current energizing both relays. After a predetermined time, in accordance with the setting of this thermal safety switch, the heating coil 44 will have become sufficiently hot to break the contacts at the point 46. As before mentioned, this thermal safety switch is of such a type that once opened, it will not reset itself, but requires manual adjustment to return it to operative position. This feature ensures bringing knowledge of the system failure to the person desiring heat.

Operation in case of momentary line failure

This condition occurs when the burner is in operation and the power line is momentarily interrupted. The main relay will, of course, be de-energized, but the stack control will still be in the hot position. It will be noticed that the contact 28 on the main relay, against which the arm 27 lies when the relay coil 16 is de-energized, will complete a circuit through the stack control when said control is in the hot position, which will short circuit both the main relay coil and the thermal safety switch. This circuit is as follows: 11, 13, 14, 15, 31, 28, 27, 26, 25, 42, 43 and 10. If the line voltage reappears while the stack control is hot, the main relay will not close because of its short circuit, and the burner will not start until the stack has cooled sufficiently to return the stack control switch to its cold position, which is a normal starting condition.

Operation as the result of manual momentary opening of the room thermostat contacts

If for any reason the room thermostat is operated manually to break the contacts 13 and 14, the energizing circuit through the main relay coil 16 will be broken, and the results will be the same as if a momentary line failure or a raise in the room temperature had de-energized the main relay. In other words, the circuit will not permit restarting of the burner motor or ignition means until the stack control has returned to its cold position, even though the room thermostat is returned to its returned position soon after its contacts are broken.

Safety features

As discussed under previous headings, if the main relay is de-energized for any reason during operation of the burner, the system cannot be restarted until the stack control has returned to its cold position, thus placing the circuit in normal starting condition. As also previously discussed, should ignition fail to take place for any reason, the entire circuit will be rendered inoperative after a predetermined time limit through the opening of the thermal safety switch 20. Should the stack control become stuck in the cold position, the automatic shunting means for the thermal safety switch would not be brought into action and, consequently, the thermal safety switch would open after the predetermined time limit even though ignition had occurred. Should

the stack control become stuck in the hot position, the burner would continue to operate until shut off by the opening of the room thermostat 12, but would not thereafter resume operation 5 until the stack control had been freed and permitted to return to the cold position.

Thus a two-relay electrical interlocking control circuit is provided in which a flame-responsive device must, during each cycle, prove itself to 10 be in operating condition, in order that the automatic operation of the burner may continue.

While I have shown and described certain embodiments of my invention, it is to be understood that it is capable of many modifications. 15 Changes, therefore, in the construction and arrangement may be made without departing from the spirit and scope of the invention as disclosed in the appended claims, in which it is my intention to claim all novelty inherent in my invention 20 as broadly as permissible, in view of the prior art.

What I claim as new, and desire to secure by Letters Patent, is:

1. In combination with means controlling fuel feed and an igniter; a control system comprising in 25 circuit, a main control switch, a current limiting means, means operable when energized to effectuate igniter operation, an electrically actuated time-limit cut-out switch, a combustion responsive device having first contacts closed only in the absence of combustion and controlling energization of said ignition means, and second contacts closed only in the presence of combustion, a relay actuating means, and switches controlled thereby including a first switch opened upon energization and controlling with said second contacts a shunt around said actuating means and cut-out switch, and second and third switches closed upon energization; the former controlling with said second contacts a shunt around said cut-out switch and the latter controlling the fuel feeding means.

2. In combination with means controlling fuel feed and an igniter; a control system including a 30 transformer and comprising a circuit, a main control switch, the low voltage secondary of said

transformer, means operable when energized to effectuate igniter operation, an electrically actuated time-limit cut-out switch, a combustion responsive device having first contacts closed only in the absence of combustion and controlling energization of said means and second contacts closed only in the presence of combustion, a relay actuating means, and switches controlled thereby including a first switch opened upon energization and controlling with said second contacts a shunt 10 around said actuating means and cut-out switch, and second and third switches closed upon energization; the former controlling with said second contacts a shunt around said cut-out switch and the latter controlling the fuel feeding means. 15

3. In a combination with means controlling fuel feed and an igniter, a control system therefor, comprising in circuit: a current limiting means; a thermostatic device; an electrically actuated time-limit cut-out switch; a main relay having 20 an actuating coil, a first switch closed when said coil is deenergized, and second and third switches closed when said coil is energized, said third switch controlling said fuel feed means; means operable when energized to effectuate igniter operation; a combustion responsive device having first contacts closed only in the absence of combustion and controlling energization of said ignition means and second contacts closed only in the presence of combustion—whereby; upon a 30 demand for heat and closure of said thermostatic switch a series circuit is established including said coil and said time-limit switch; upon successful combustion said ignition means is deenergized and a second series circuit is established including 35 said thermostatic device, said coil, said second switch, and said second contacts, whereby a shunt circuit is provided for said time-limit switch; and upon deenergization of said main coil a third circuit is established shunting said main coil and 40 cut-out switch including in series said thermostatic device, said first switch, and said second contacts, thereby preventing energization of said main relay until reclosing of said first contacts.

EARLE W. BALLENTINE. 45
